SOCKET HEAD SCREW

Gerhard H. J. Baule, Salina, N. Y.

Application September 5, 1945, Serial No. 614,458

3 Claims. (Cl. 85—45)

1

This invention relates to threaded members or screws of various types, and has for its object a screw particularly for mass production or for assembly work by automatic machines, although the screw is also operable by hand screw drivers, which screw is provided with a driving-tool-receiving recess or socket for receiving the tool of such shape or formation that when the tool is received in the socket or recess, the screw because of the shape of the recess, is held from falling off while being transferred from the receiving or pick-up station, magazine or hopper to the place the screw is to be applied and the tool releases from the screw by a withdrawing movement of the tool. More specifically, it has for its object a screw, the head of which is formed with a non-circular or angular driving tool receiving socket, at least a portion of which is twisted slightly or of spiral formation of less than one convolution, the spiral preferably leading in such direction that the tool leads into the socket during turning in a driving direction and pulls out as the tool frees itself of the screw by withdrawing the tool with no turning force applied.

The invention consists in the novel features and in the combinations and constructions hereinafter set forth and claimed.

In describing this invention, reference is had to the accompanying drawings in which like characters designate corresponding parts in all the views.

Figure 1 is an enlarged isometric view of a screw embodying this invention.

Figure 2 is a plan view of parts seen in Figure 1.

Figure 3 is a fragmentary isometric sectional view through the head of the screw and contiguous portions of the shank.

Figure 4 is a view similar to Figure 3 of a slightly modified form.

Figure 5 is a view similar to Figure 4 of a second modified form.

Figure 6 is a sectional view of the screw head and one form of driving tool for the screw.

1 and 2 designate respectively the inner and outer recesses of a driving-tool-receiving socket, the socket being formed axially in the head 3 of a screw 4, the inner recess 1 only being twisted or of helical formation of less than one convolution, the helical curve being clearly shown by the corners 5 formed by the side walls of the inner recess 1. The socket, as here shown, is hexagonal.

The outer recess 2 is here shown as, and preferably is, of larger diameter than the inner re-

2

cess 1, but as indicated by its corner lines 6 of its polygonal sides is here shown as not of helical formation, but it may be helical of different angle.

In the form shown in Figures 1, 2 and 3, the wall of the outer recess 2 is beveled or tapers from the outer face of the screw to the upper end of the inner recess 1. As shown in Figure 4, the outer recess 20 is formed with a circumferential wall 7 and a bottom wall 8 which meet at an angle, here shown as a right angle. The difference between the operation of the recesses 2 and 20 will be hereinafter set forth. In Figure 5, the spiral formation of the inner recess is provided by spirally extending splines 8. The sockets may be formed by any suitable process and the socket here shown has a flat bottom, although if formed with a boring tool would incidentally have a conical bottom.

The socket in the head of the screw is for receiving a screw-driving tool of any suitable construction, and the outer recess coacts with the driving tool to hold the screw from dropping off the tool after it has been picked up by the tool and is being transferred to the hole in which it

is to be screwed. The tool itself may be of any construction, and in Figure 6, 10 designates the shank of a tool, which is actuated in any suitable manner, the shank having a head 11 of spiral formation for turning into the socket or recess 1 thereof. An axial movable locking member, as the sleeve 12, is slidably mounted on the shank 10 of the tool, this sleeve being shown as beveled at its lower end for entering the recess 2. This also is hexagonal, or the same shape in cross section as the recess 2. The carrier 14 is here shown as guided in grooves in a collar 15 secured to the shank 10 of the tool. The locking sleeve 12 is shown as pressed into locking position by the spring 13 encircling the shank 10 and interposed between the collar 15 and the sleeve 12. As the tool enters the socket, the sleeve 12 is pushed back until the angles or corners of the sleeve align with the corners of the outer recess. When the spiral end of the tool enters the inner recess to some extent, the end of the sleeve will contact the recess 2, but at this time, the non-circular shape of the sleeve end is not lined up with the non-circular shape of the recess.

Continuing the insertion of the spiral end of the tool by combined axial and twisting movement, the sleeve will partake of the twisting movement, but will move relative to the tool shank in an axial direction opposite to the axial movement of the shank against the action of the spring 13, which will be compressed. When the helical end of the tool shank

reaches a position near the bottom of the helical recess, the end of the sleeve 12 will be aligned with and fit into the recess 2 and will hold the screw from dropping by turning off the driving tool, the sleeve still being yieldingly pressed into position by the spring 13. The locking sleeve may be withdrawn against the action of the spring 13 by withdrawing the carrier 14 for the sleeve. This carrier may be actuated in any suitable manner. In the form shown in Figure 3, the 10 tapered bottom of the outer recess 2 serves as a cam to dislodge the sleeve 12 and overcome the locking action when sufficient withdrawing force is applied to the driving tool 10. Such pulling will tend to turn the tool, and hence the sleeve, in a retrograde direction. In the form shown in Figure 4, the driving tool 10 is positively held from retrograde turning, when a withdrawing force is applied, because the locking sleeve 12 fits the angular channel or rabbet or recess 20 formed by its circumferential and bottom walls 7 and 8. Hence in the form shown in Figure 4, it is necessary to mechanically and forcibly withdraw the locking member or sleeve 12 before the driving tool can be pulled from the screw or before the 25 spiral head of the driving tool can be withdrawn from the spiral recess 1 of the screw.

The method of forming the screw with the driving recess forms no part of this invention.

In operation, the screw locks itself on the tool, 30 due to the spiral tool-receiving recess 1 and the locking recess 2.

What I claim is:

1. A screw having an axial, driving-tool-fitting socket for a tool of complementary contour, the socket including a non-circular inner recess of helical formation in which the helices at the corners formed by the helices extend in a general direction lengthwise of the axis of the socket and the screw substantially the depth of the recess, and in which each is less than one convolution, and an outer recess in the form of a countersink

at the entrance of the former recess formed with corners aligned with the helices to restrain dropping of the screw off the tool.

2. A screw having an axial, polygonal, driving-tool-fitting socket for a tool of complementary contour, the socket including an inner recess, the sides of which extend in a general direction parallel to the axis of the screw, the corner lines of the polygonal formation being helical and less than one convolution, and an outer tool lock receiving recess in the form of a countersink at the entrance of the former recess and formed with corner lines in line with the corner lines of the helices.

3. A screw having an axial, polygonal, driving-tool-fitting socket for a tool of complementary contour, the socket including an inner recess, the sides of which extend in a general direction parallel to the axis of the screw, the corner lines of the polygonal formation being helical and less than one convolution, and an outer tool lock receiving recess in the form of a countersink at the entrance of the former recess, the outer recess being formed with corner lines in line with the outer ends of the helices, the bottom of the countersunk recess being beveled.

GERHARD H. J. BAULE.
